US0D1082149S

(12) **United States Design Patent** (10) **Patent No.:** **US D1,082,149 S**
(45) **Date of Patent:** **** Jul. 1, 2025**

(54) **BACK SCRATCHER**

(71) Applicant: **Shenzhen Yuecheng Yuezhen Industrial Development Co., Ltd,**
Shenzhen (CN)

(72) Inventor: **Zhanyue Li**, Guangdong (CN)

(**) Term: **15 Years**

(21) Appl. No.: **35/521,566**

(22) Filed: **May 23, 2024**

(80) **Hague Agreement Data**

Int. Filing Date: **May 23, 2024**

Int. Reg. No.: **DM/238083**

Int. Reg. Date: **May 23, 2024**

Int. Reg. Pub. Date: **Jul. 5, 2024**

(30) **Foreign Application Priority Data**

Mar. 21, 2024 (CN) 202430148839.4

(51) **LOC (15) Cl.** **28-99**

(52) **U.S. Cl.**

USPC **D28/91.2**

(57) **CLAIM**

The ornamental design for a back scratcher as shown and described.

DESCRIPTION

1. Back scratcher

1.1 : Perspective

1.2 : Perspective

1.3 : Front

1.4 : Back

1.5 : Left

1.6 : Right

1.7 : Top

1.8 : Bottom

The broken lines shown in the drawings depict portions of the back scratcher that form no part of the claimed design.

1 Claim, 8 Drawing Sheets
